UNITED STATES PATENT OFFICE.

FERDINAND KOOPMANN, OF MUNICH, GERMANY.

SAFETY-BELT.

SPECIFICATION forming part of Letters Patent No. 330,132, dated November 10, 1885.

Application filed March 5, 1885. Serial No. 157,823. (No model.)

To all whom it may concern:

Be it known that I, FERDINAND KOOPMANN, of the city of Munich, Germany, have invented a new and Improved Safety-Belt, of which 5 the following specification is a full, clear, and exact description.

This invention relates to a belt for holding children in their cradles without impeding the freedom of their movements. The belt 10 may also be used for securing delirious patients, and for similar purposes.

The invention consists in a belt having two flaps adapted to be folded around the body of the child or patient, also, in the details of 15 construction hereinafter more fully pointed out.

The drawing represents a perspective view of my improved belt.

The letter A represents a belt made of soft 20 leather, linen, or similar material. a a are strings attached to its ends, by which it may be tied to a bed or carriage. b b' are two flaps projecting upward from the belt A. The flap b is permanently attached to the belt, while

the flap b' is secured to a loop, c, which is 25 slipped over the belt and is free to slide thereon. The free edges of the flaps b b' are provided with buttons and slits, so that they can be fastened together.

In use the belt A is placed upon the mattress and tied at its ends by means of the strings a a. The child is then laid on the belt between the flaps b b', which are then buttoned over its body. In this way the child is held in place, while at the same time it has the free 35 use of its limbs.

I claim as my invention—

1. The combination of belt A with the flaps b b', secured to one of its sides, and adapted to be connected, substantially as herein shown 40 and described.

2. The combination of belt A with fastening devices a a, flap b, and flap b', secured to loop c, substantially as specified.

FERDINAND KOOPMANN.
